UNITED STATES PATENT OFFICE.

SAMUEL W. FROST, OF BOSTON, MASSACHUSETTS.

SAFETY-PORT FOR COAL-HOLES.

Specification of Letters Patent No. 12,623, dated April 3, 1855.

To all whom it may concern:

Be it known that I, SAMUEL W. FROST, of Boston, in the county of Suffolk and State of Massachusetts, have invented a new and useful Safety-Port for Coal-Vaults; and I do hereby declare that the same is fully described and represented in the following specification and the accompanying drawings, letters, figures, and references thereof.

10 Of such drawings, Figure 1, denotes a top view of the said safety port as it appears when closed. Fig. 2, is a top view of it when it is opened. Fig. 3, is an end elevation and Fig. 4, is a vertical, central and longitudinal section of it, the last two views showing the port in an open state. Fig. 5, exhibits a side view of it as closed.

15 In these drawings, A, exhibits a metallic frame, which has a rectangular or other proper form such as can be inserted and fixed in the sidewalk of a street and directly over a coal vault formed beneath such. This frame A, is provided with a closing door or cover B, which turns on hinges or journals 20 arranged at or near one end of it, (see *a, a*) so as to enable the door to be raised from a horizontal into an upright position.

25 So far as the frame and door or cover is concerned it may be essentially like what is commonly applied to coal vaults, except that it is rare to apply the cover to the frame by 30 hinges.

It is well known that in consequence of the cover being left off, serious accidents often happen, as persons are liable to fall 35 into the vault or its mouth or opening, either breaking their legs or otherwise suffering severe injury. The frequent recurrence of these accidents has rendered it very 40 necessary to devise some means for their prevention, and this is the purpose of my improved safety port.

I combine with the frame, A, or its opening and the door, B, a safety guard which is 45 composed of two quadrant arcs, C, C,

formed of metal or other suitable material. They are made to project from the underside of the cover, B, and to extend into the opening of the frame, A, as seen in the drawings. 50

Near their lower corners they are connected together by a crossbar or plate, D, which when the door, B, is elevated into a vertical position is made to extend above the frame, A, as seen in the drawings, the same 55 being for the purpose of serving as a guard to prevent a person's foot from slipping from the adjacent or front end of the frame A, into the coal vault. The guards, C, C, constitute guards to prevent a similar accident 60 when a person is approaching the coal vault opening from either side of it, the other or rear side of the opening being protected by the cover B.

In order to maintain the safety port open, 65 a pin or bolt E, may be extended through it and the frame A, as seen in Fig. 4. The cover, B, may be furnished with a sliding bolt F, so that when it is closed such bolt may be shoved into the bolt hole made in 70 the frame A.

When the door, B, is elevated into a vertical position, coal may be thrown into the vault through the open space between the quadrants C, C, and the cross bar or 75 guard D.

What I claim as my invention is—

Combining with the door, B, and the frame, A, or the vault opening, a safety guard applied thereto substantially in manner and for the purpose as hereinbefore specified. 80

In testimony whereof I have hereunto set my signature this twenty sixth day of February A. D. 1855.

SAML. W. FROST.
